UNITED STATES PATENT OFFICE.

CARL E. BALBACH, OF OMAHA, NEBRASKA.

CLOTHES-LINE-REELING DEVICE.

No. 889,888.

Specification of Letters Patent.

Patented June 9, 1908.

Application filed October 25, 1907. Serial No. 399,144.

To all whom it may concern:

Be it known that I, CARL E. BALBACH, a citizen of the United States, residing at Omaha, in the county of Douglas and State 5 of Nebraska, have invented certain new and useful Improvements in Clothes-Line-Reeling Devices, of which the following is a specification.

This invention relates to improvements in 10 clothes-line reeling device, intended as a convenient article for domestic use for reeling and housing clothes lines, and to afford means by which the line may be made taut after it has been drawn from the reel.

15 The invention has reference to a structure of few parts and which, therefore, may be economical in manufacture, and which will be efficient for the purposes designed; and consists of the novel combination and arrangement of parts fully described herein, pointed out by the claims and illustrated in 20 the drawing, wherein,—

Figure 1 is a vertical, end view of the invention mounted upon a post, the latter being partly broken away. Fig. 2 is a vertical front view of the invention, a part of the circular covering or shell being broken away. Fig. 3 is a view sectioned between lines *a a* 25 and *b b* of Fig. 1, to illustrate structure of spool and side plates. Fig. 4 shows a fragment of an end plate, broken away to disclose a part of the reel, and to show a part of the circular cover and rollers in section. Fig. 5 is a plan view of a rectangular plate used to 30 form a shell or cover, and Fig. 6 is a front view of the shell or circular wall formed by bending the plate shown in Fig. 5.

Referring to the drawing for a more particular description, numeral 1 indicates a 35 pair of reel-arms formed as parallel disks, rigidly secured upon and near the ends of shaft 2, the latter having aperture 3 transversely formed therein, and the construction, as described, defines a spool or reel upon 40 which the clothes line 4 may be wound.

A circular housing-box 5 is formed by use 45 of substantially circular end-plates 6 preferably constructed of cast metal, each having an inturned flange 7 at its periphery, these 50 end-plates being disposed parallel; and I employ a cylindrical shell 8 which may be conveniently formed by bending the rectangular plate 8' (Fig. 5.); this plate is preferably 55 constructed of galvanized iron, and this shell is seated transversely between end-plates 6, upon the inner sides of flanges 7 of the end-

plates; and shell 8 has oppositely-disposed terminals 9, forming an aperture 10 therebetween, this aperture being indicated by the broken lines *c c* in Fig. 2. Since disks 1 have 60 a less diameter than end-plates 6, there is sufficient space outside the plane of the disks for use of transverse bolts 11 for securing the end-plates together, and they are thus secured; covering 8 has a seating outside the 65 plane of the bolts and in contact with the inner side of flanges 7; and shaft 2 has end-bearings in the central openings 12, formed in the end-plates. Bases 13, with flat bearing-faces 14 are formed upon the perimeter 70 of the end-plates; these bases are similarly disposed, and are formed with extensions or holding-flanges 15; and the housing-box, with the reel seated therein may be secured to extend horizontally, upon any suitable 75 support, as post 16, by use of bolts 17.

As thus described, housing-box 5 provides a convenient means for storing a clothes line, the latter being secured to chain 18 one end of which is secured to shaft 2 by traversing 80 aperture 3 of said shaft, the chain being extended through aperture 10 of the housing-box, its opposite end being provided with a ring 19 of less diameter than the size of aperture 10. By turning crank 20, the line 85 may be wound upon shaft 2 between disks 1 and may be housed when not in use. Upon the end of shaft 2, opposite the crank, and exteriorly of the box, is secured ratchet 21 which is engaged by the pawl 22, mounted 90 upon the end-plate, the operation of these parts being to hold the spool or reel and prevent unwinding of the line, after said line has been drawn and operatively placed, and, in connection with the crank, to cause 95 the line, after said line has been drawn out and operatively placed, to become and remain in a strained or taut condition.

In order that the clothes line, at time of 100 unwinding the reel, may be protected from a contact with the terminal edges *c c* of the cover or shell, I employ transversely and oppositely disposed rollers 23 having end-mountings upon bearing-plates 24, the latter being secured adjacent end-plates 6 and extended outwardly of cover 8; and bearing-plates 24 are formed with oppositely-disposed curved contact-flanges 26; flanges 26 are also disposed transverse to rollers 23, and 105 said flanges and rollers 23 extend beyond the 110 terminal walls *c c* which define opening 10 of the circular shell 8; the clothes line when

moving, therefore, makes contact only with rollers 23 or flanges 26 and is protected from injury.

Chain 18, with ring 19 exteriorly of casing 8, is secured to shaft 2 at the time of assembling the parts, and this arrangement, it will be noted, affords a convenient means for attaching the line.

While the device, when operatively mounted, should extend outwardly or horizontally from bearing-faces 14, it may be secured to any suitable, vertical surface for use and, of course, remains as a fixture when thus mounted. At the time of unwinding the line from the reel, the pawl may be manually turned from engagement with the ratchet.

What I claim as my invention is,—

In a clothes line reel the combination with a casing, of means for securing said casing to a fixed support, a rotative reel mounted in

said casing, a pawl and ratchet connection between said reel and said casing, there being an opening formed through the front wall of the casing, a pair of horizontally disposed rollers extending entirely across the opening of said casing, one of said rollers being located at the lower side of said opening and the other of said rollers being located at the upper side of said opening, a pair of bearing plates secured to said casing in which said rollers are journaled the outer portions of said plates being bent toward each other and inwardly between the rollers to form contact flanges.

In testimony whereof I have affixed my signature in presence of two witnesses.

CARL E. BALBACH.
